UNITED STATES PATENT OFFICE.

MERRILL M. WILCOX, OF SAGINAW, MICHIGAN.

TAPPET.

Original application filed September 10, 1919, Serial No. 324,959. Divided and this application filed May 28, 1921. Serial No. 471,836.

To all whom it may concern:

Be it known that I, MERRILL M. WILCOX, a citizen of the United States, residing at Saginaw, in the county of Saginaw and State of Michigan, have invented certain new and useful Improvements in Tappets; and I do hereby declare the following to be a full, clear, and exact description of the invention, such as will enable others skilled in the art to which it appertains to make and use the same.

This invention relates to valve-actuating tappets for internal combustion engines, and pertains more particularly to certain novel features of construction embodied in a valve tappet as a new article of manufacture, whereby I am enabled to produce an exceptionally light but strong tappet, with an enlarged base of very hard metal such as case-hardened steel to contact with the engine cam, and an internally threaded plug in the opposite end of the tappet to receive the bolt or other adjustable device that contacts with the stem of the valve.

The arrangement of parts in my improved tappet construction is such that they can be easily, quickly and accurately assembled and the individual parts can be manufactured at small cost and by automatic machines of standard construction, insuring uniformity of size and shape and weight.

With the foregoing and certain other objects in view, which will appear later in the specification, my invention comprises the devices described and claimed, and the equivalents thereof.

My invention is illustrated in the accompanying drawing, showing a part longitudinal sectional view of a tappet embodying my improvement.

As is clearly shown in the drawing, the tappet consists of a shell or body 1 preferably comprising a solid bar of metal formed with a longitudinal bore extending from one end of the tappet toward the other end, the bore being of lesser length than the length of the body, whereby an integral closure is left at one end of the body, that part of the body which is bored being in the form of a thin-walled tube.

Secured to the other end of the body 1 is a head 2 formed of a separate piece of metal, heat-treated and hardened.

A projecting cylindrical shank is formed on the head 2 and is accurately fitted to and preferably received in the bore of the body 1, to which it is secured by spot welding, as indicated at 3, or if desired, the shank may be secured in the tube in any other suitable manner, as for example, by screwing it into place, or by swaging, as described in my co-pending application, Serial No. 324,959, in which the broader aspects of the head and body construction are described and claimed.

In forming the tappet, the body 1 is first made by drilling to form the longitudinal bore, leaving the integral closure 4, and the closure 4 is then drilled and tapped, as at 5, to receive a bolt, not shown, against which the valve stem contacts in action. The shank of the head 2 is then pressed into the bore of the body 1 and secured thereto preferably by spot welding, as at 3.

The use of an independent hardened head 2 makes it possible to use the integral closure 4 and hollow tubular body 1, since the boring is done from the head end before the body and head are assembled.

In the event of a defective piece being produced, the defective member may be discarded before assembling, avoiding the necessity of discarding the entire tappet, as would be the case if the case-hardened base and the head were formed of one piece of metal and afterward heat-treated.

By making the head of an independent piece of metal and heat-treating it before assembling it on the body, the chance of spoiling the body during heat treatment is eliminated.

Having thus described my invention, what I claim and desire to secure by Letters Patent is:

As an article of manufacture, a tappet comprising a hollow cylindrical body of substantially uniform external diameter throughout its length, said body bored throughout a part only of its length, thereby forming a closure integral with said body at one end, a cam-contacting head having a hardened face and an elongated cylindrical shank of reduced diameter, said shank received in the other end of said tubular body and welded thereto.

In testimony whereof I affix my signature.

MERRILL M. WILCOX.
